METHOD OF SPLICING RUBBER THREAD

John F. Cavanagh, Providence, R. I.

Application October 16, 1941, Serial No. 415,271

8 Claims.

(Cl. 28—1)

This invention relates to the splicing, as opposed to knotting, of single strands of rubber known to the trade as rubber thread. The knotting of rubber thread is highly objectionable inasmuch as the knot acts as a stub in passing through guides and needle hooks and furthermore, in most instances, shows up as an imperfection in finished fabrics.

One of the objects of this invention is to effect a union of rubber strand ends which will be sufficiently strong so that these ends will not pull apart as elongation of the yarn occurs.

Another object of the invention is to join the ends without producing an obstruction to the functioning of the rubber yarn in fabrication mechanisms in which the yarn may be used.

A further object of this invention is the provision of a simple method of procedure for attaching together the ends of rubber thread.

A further object of the invention is to secure the ends of rubber thread by the wrapping of an adhesive material about the ends thereof.

With these and other objects in view, the invention consists of certain novel features of procedure, as will be more fully described, and particularly pointed out in the appended claims.

In the accompanying drawing:

Fig. 1 is a perspective view of two ends of rubber thread joined together in accordance with my improved method.

Fig. 2 is a sectional view of a carrier for a binding film with two ends positioned for wrapping of the binding film thereabout.

Fig. 3 is a sectional view illustrating the binding strip as partially rolled about the overlapped thread ends.

Fig. 4 is a sectional view illustrating the complete wrapping.

Fig. 5 is a view similar to Fig. 2 but shows the thread ends positioned in a different relation than shown in Fig. 2.

Fig. 6 illustrates the commencement of the wrapping of the binding strip about the thread ends in their relation shown in Fig. 5.

Up to the advent of my present invention I knew of no good practical way to join severed rubber thread or strand ends together without knotting them, thus producing by such knotting an enlargement at the point of union which will prevent the thread from passing freely through guides, needle eyes or hooks in which it is used for the formation of fabric. In order that the ends of such rubber or elastic yarn may be joined together, I have provided an arrangement for splicing the ends without knotting and by rolling

5 a thin adhesive film about the ends in such a manner that the ends are reduced and in the finished product no detrimental enlargement of the joined ends occurs, thus permitting the thread to be used in the usual manner for fabrication and providing a junction which is indistinguishable in the finished fabric; and the following is a more detailed description of the present embodiment of this invention, illustrating the preferred procedure by which these advantageous results may be accomplished:

With reference to the drawing, 10 designates one thread end and 11 another thread end portion both of rubber which I desire to splice together. The mechanism which I have found most useful for accomplishing this result is described in detail in my copending application Ser. No. 364,405, filed November 5, 1940, wherein I have claimed the apparatus for accomplishing the result here attained. The steps, however, which are performed by this apparatus are unique and I have illustrated sufficient of the method performed in this drawing for a complete understanding of the steps of procedure which I have taken to accomplish the desired result.

In Fig. 2 a carrier of some material, such, for instance, as highly polished Celluloid, designated 12 has mounted thereon a thin film 13 of unvulcanized adhesive rubber or rubber which has been only partially vulcanized. The inherent adhesiveness of this material causes it to stick to the carrier 12 and extend along its surface. The ends 14 and 15 of the rubber threads 10 and 11 are positioned in contact with each other and with this adhesive film 13 and in overlapped relation as shown in Fig. 2 and then some flat surface 16 engages these threads and by relative movement to the carrier 12 and its backing-up support rolls the threads 10 and 11 so as to wrap the adhesive film 13 about the threads. This rolling of the threads in this manner serves to tear the adhesive film which is of very thin character and sticks to the thread from the body portion 18 of the film to provide the inner edge 19 of the wrapping such as illustrated in Fig. 3. The rolling of the threads together in this manner upwardly as shown by the arrow 20 in Fig. 3 completes the wrapping with the end edge 21 spirally coiled about the wrapping as shown in Fig. 4 for the completion of the wrap designated generally 22 in Figs. 1 and 4.

In some cases instead of overlapping the ends 14 and 15 I have shown in Fig. 5 these ends positioned in an abutting relation and by engagement with the threads in this abutting relation and a

rolling as heretofore described a wrapping will commence at its inner edge 25 (see Fig. 6) and will be completed by the spiral coiling of the film so that the same will be disposed as heretofore indicated in Fig. 4.

This film 13 may be deposited on the Celluloid in liquid form from which the solvent evaporates leaving a very thin film on the Celluloid or guide apron or carrier for manipulation as above indicated. The film is sufficiently strong that when wound once or more times about the ends of the rubber thread will serve to bind the film into firm contact with each of the ends of the thread and secure the thread ends together whether they be overlapped and compressed or whether they be left in substantially their full diameter and abutted and wrapped in this manner.

By this arrangement yarn ends are spliced together so as not to materially enlarge their diameter and thus permit the thread to be used in machines and through openings the same manner as were the thread extruded in its original size.

I claim:

1. The method of splicing rubber thread which consists in wrapping a thin film of adhesive material about the adjacent end portions of the thread, while maintaining the wrapping the same film shape at the end of the wrapping as at the beginning of the wrapping.

2. The method of splicing rubber thread which consists in wrapping a thin film of rubber about the adjacent end portions of the thread, while maintaining the wrapping the same film shape at the end of the wrapping as at the beginning of the wrapping.

3. The method of splicing rubber thread which consists in wrapping a thin film of adhesive material about overlapped end portions of the 40

thread, while maintaining the wrapping the same film shape at the end of the wrapping as at the beginning of the wrapping.

4. The method of splicing rubber thread which 5 consists in wrapping a thin film of rubber about overlapped end portions of the thread, while maintaining the wrapping the same film shape at the end of the wrapping as at the beginning of the wrapping.

10 5. The method of splicing rubber thread which consists in overlapping the end portions of the thread to be spliced and rolling the overlapped ends along an apron having thereon a thin film 15 of adhesive rubber to wrap the film about the overlapped rubber ends, while maintaining the wrapping the same film shape at the end of the wrapping as at the beginning of the wrapping.

6. The method of splicing rubber thread which 20 consists in wrapping a thin film of rubber about the abutted end portions of the threads to be spliced, while maintaining the wrapping the same film shape at the end of the wrapping as at the beginning of the wrapping.

7. The method of splicing rubber thread which 25 consists in positioning the thread ends in abutting relation on a thin film of rubber and rolling the ends to wrap the film about the abutted ends of the thread, while maintaining the wrapping the same film shape at the end of the wrapping as at the beginning of the wrapping.

30 8. The method of splicing rubber thread which consists in positioning the thread ends in abutting relation on a thin film of rubber and compressing and rolling the ends to wrap the film 35 about the abutted ends of the thread, while maintaining the wrapping the same film shape at the end of the wrapping as at the beginning of the wrapping.

JOHN F. CAVANAGH.
